UNITED STATES PATENT OFFICE

WILLIAM G. DUNN, OF CLARINDA, IOWA

DESIGN FOR AN ABRASIVE HOLDER

Application filed January 25, 1932. Serial No. 42,611. Term of patent 3½ years.

To all whom it may concern:

Be it known that I, WILLIAM G. DUNN, a citizen of the United States, and a resident of Clarinda, in the county of Woodbury and State of Iowa, have invented a certain new, original, and ornamental Design for an Abrasive Holder, of which the following is a specification, reference being had to the accompanying drawing, forming part thereof.

abrasive holder embodying my design, and illustrating the holder as viewed from one corner thereof.

Figure 2 is a bottom perspective view of the same as viewed from one side thereof.

I claim:

The ornamental design for an abrasive holder as shown.

Des Moines, Iowa, January 18, 1932.

WILLIAM G. DUNN.
